WELL PUMPING UNIT

George T. Humphrey, Dallas, Tex.

Application October 17, 1935, Serial No. 45,459

6 Claims. (Cl. 74—103)

This invention relates to oil field equipment and it has particular reference to certain new and useful improvements in well pumping units.

The principal object of the invention is to provide in a well pumping unit, a convertible frame whose peculiar construction is such that it may be adapted to three or more systems of pumping oil, gas or water wells, inasmuch as it is provided with equipment, which, with but slight alteration may employ either the cable for flexible connection with the pump or by a walking beam. In either case, flexibility is insured between the power and actual engagement of the cable or pump rods with the traveling valve or pump, arranged for reciprocation in the well.

Another and important object of the invention is to provide a self-contained unit, that is to say, a unit in which the power source may be included in the structural combination in such manner that the greatest efficiency may be obtained therefrom without requiring a space greater than that which would be ordinarily occupied by the unit separately.

Another object of the invention is to provide a pumping unit, whether cable or walking beam actuated which will insure absolute perpendicular travel of the pump rods in the well or tubing, thereby obviating the usual expense and difficulties encountered due to crystallization and consequent breakage of the rods when they are subjected to lateral stresses and binding action where no attempt is made to compensate for the variation in movement between the walking beam and polished rod of conventional design.

Yet another and most important object of the invention is to provide a combined power wheel and counterbalance whose novel characteristics reside in the fact that it is self contained and various weight adjustments may be obtained within the peripheral confinement of the wheel. This wheel is so constructed that suitable counterbalanced weights may be moved relative to its rotating axis by only a single workman to obtain from zero to maximum degree of counterbalancing effect, depending upon the rod, by the simple movement of the weight relative to the axis or periphery of the wheel.

Still another object of the invention is to provide in the power and counterbalance wheel a reinforcing medium which will resist any tendency of the adjustable weight to vary the true alignment of the wheel, which is unlikely due to the fact that the force is outward, but in addition to this, the reinforcement provided insures against fracture of any of the structural elements of the

wheel, should it be subjected at any time to any undue stresses in operation.

With the foregoing objects as paramount, the invention has particular reference to its salient features of construction and arrangement of parts which will become manifest as the description proceeds, taken in connection with the accompanying drawings, wherein:—

Figure 1 is an elevational view of one form of the pumping unit, showing its convertible frame 10 and adaptation as a cable operated pumping unit.

Figure 2 is a front elevation of Figure 1.

Figure 3 is a plan view, with certain parts of the upper portion broken away, to illustrate progressively the drive from the power source to the counterbalances.

Figure 4 is a fragmentary detail view in perspective showing the preferred adjustment for the counterbalances.

Figure 5 is a detail view in perspective showing a joint retaining clamp for the pump unit cable which connects the cable with the connection shown in Figure 6.

Figure 6 is a detail view of the cable connection.

Figure 7 shows a method of securing the cables 25 to a cross head which is a part of the cable clamp, connecting the pump unit cables with the polished rod.

Figure 8 is a modified form of counterbalance weight adjustment.

Figure 8A is a plan view of a complete structure, part of which is shown in Figure 8, illustrating the modified form of counterbalance adjustment.

Figure 9 is a perspective view of the convertible 35 pump unit frame, showing its adaptation for a walking beam.

Figure 10 is a sectional view on lines 10—10 on Figure 9.

Figure 11 is an elevational view of the power 40 and counterbalancing wheel.

Figure 12 is a view on lines 12—12 on Figure 11.

Figure 13 is a sectional view of the upper segment of the wheel shown in Figure 12, differing only in that the periphery is channeled and thus 45 adapted to receive a V-belt, and

Figure 14 is a side elevation of the upper segment of the power and counterbalancing wheel showing gear or sprocket teeth for the reception of companion gear teeth or a sprocket chain.

Continuing with a more detailed description of the drawings, reference is primarily made to Figure 1 in which one form of the invention is shown in which reciprocation of the pump rod assembly is obtained through the medium of a cable, whose 55

flexibility is insured against other than strictly perpendicular travel of the pump rods or polished rods as the case may be. It may be mentioned at this point that the frame of the pumping unit, to be described presently is convertible, that is to say, it may be adapted for cable use as shown in Figure 1 or to receive a walking beam as illustrated in Figure 9.

However, in the case of the structure shown in Figures 1 and 2, 1 indicates a base constructed preferably of I-beams superimposed upon which are substantially upright members and angular supports 3. Bearings 4 are situated upon the upper end of the uprights 2 and in these bearings is journaled the ends of a shaft 5, the latter carrying a peripherally grooved sheave or pulley 6, to which reference will again be made presently.

Substantially midway between the top and base of the frame are transverse or horizontally disposed members 7, one of which is situated on either side of the frame. An enlarged view of the member 7 and their relationship with the frame is shown in plan view in Figure 3. Bearings or journal boxes 8, similar to the bearings 4, are disposed on the members 7. The purpose of these bearings 7 is to receive stub shafts 9. Upon the inner ends of each of said shafts is affixed the members 10 of a counterbalance. The counterbalance will be broadly designated by the reference character 10 in the course of the detail description thereof to follow presently.

Interposed between the members of the counterbalance 10 is a shaft 11, shown in detail in Figure 4, and by virtue of bearing plates 12 and their adjustability relative to ends of counterbalance members 10, the weight imposed by the counterbalance on the axes of the shaft 9 may be varied, depending of course on the load carried by the rod reciprocating cable 13.

Referring to Figure 4, it will be noted that each member 10 of the counterbalance is grooved or recessed at 14 and is provided with a reinforcing rib 15 to strengthen the members 10 which are weakened presumably by the groove or recess 14. This structure is somewhat modified in the Figure 8, to which reference will be later made. The fragmentary member 10 shown in Figure 4 provides apertures 16 to receive bolts 17 which secure the bearing plates 12 in the recess 14. By removing 50 these bolts, the plate 12 may be moved in the recess or groove 14, thus changing the effect of the counterbalance as explained.

Carried upon the shaft 11, whose axis is obviously offset with respect to the axes of shaft 9 to obtain the necessary crank effect, carries a grooved sheave 18 as shown in Figure 3. The preferred construction requires that a roller bearing 19 be disposed within the sheave 18 and which surrounds a bronze bushing 20. This construction minimizes wear and reduces the friction to the minimum.

Carried upon the outer ends of shafts 9 are drive wheels 21. These wheels are likewise peripherally grooved to receive a plurality of belts 22. These belts are preferably V-shape in transverse section and surround similarly grooved pulleys 23, mounted upon the ends of a transverse shaft 24. A drive wheel 25, likewise having a series of peripheral grooves is mounted upon shaft 70 24 and V-type belts 26 surround this wheel and a similar but smaller wheel or pulley 27 mounted upon the armature shaft 28 of the motor 29. From the foregoing it is apparent that when the motor 29 is set into operation, the wheel or pulley 75 is rotated to impart rotation to the shaft 24 and

wheels 21, which in turn impart rotation to the stub shaft 9 to thereby rotate the counterbalance 10. This action obviously causes the axis of the sheave 18 to swing in a circular path about the common axis of the two shafts 9, but in so doing, the sheave 18 oscillates rather than rotates since it is around this sheave that the cable 13 is passed and which continues over the large wheel 6 and supports the cross member 30, shown in detail in Figure 7. Continuous operation in accordance 10 with the foregoing actuates the polished rod 31 in a strictly perpendicular path without deviation and therefore minimizes crystallization and possible consequent breakage.

It is apparent that the counterbalance 10 as 15 well as the wheels 21, which are provided with counterbalance means 32, may be weighted to the desired capacity or load carried, to overcome as much as possible the strain to which the frame would otherwise be subjected. The frame as 20 shown in Figure 7 is equipped with suitable braces 33, 34, and 35.

The structure as described and shown in Figure 1 employs but a single cable 13 but if found desirable, two cables may be employed by using 25 the device shown in Figure 5, which is comprised of a sleeve or collar 36 through which is passed a stub shaft 37, the shaft being in substitution of shaft 11 shown in Figure 3. Roller bearings 38 surround the shaft 37. Bifurcated members 9 30 extend outward from the sleeve 36 and are recessed or hooked at 40 to receive pins 41. Referring to Figure 6, the ends of the cables 42 are suitably secured in sockets provided by the protuberances 43 midway between the ends of the pins 41 and these pins are loosely disposed in the recesses 40 of the bifurcations 39 in order that the protuberances 43 will extend between the bifurcations 39.

Accordingly, assuming that the ends of the 40 shafts 37 are journaled in the boxes 12 secured to the counterbalance 10, the cables 42 will overreach the grooved wheel 6 and depend to receive the cross member 30, shown in Figure 7, which in turn, through the rods 44, suspends the 45 pump rod assembly in the well. Should one of the cables 42 break, the companion cable will hold the load and prevent the rod assembly from dropping into the well until the broken cable can be repaired. Of course, in case of such breakage the 50 sleeve 36 will be rotatably displaced in the hooks of the bifurcated members 39 thereby holding the pins 41 intact.

Referring to Figure 7, it will be noted that the ends of cable 13 are secured in the cross-member 55 30 by "mule tailing" as shown or by any other suitable means.

It has been stated in the preamble and in the course of the foregoing description relating to the cable operated pumping unit that the frame 60 per se is convertible and which feature is among the most important of the objects of the invention.

The following description will deal with the same frame employing a walking beam as a modified example of the invention.

Accordingly, reference is primarily made to Figure 9 showing a perspective view of the modified form of the invention. The reference numeral 45 denotes the base structure comprised 70 preferably of I beams superimposed upon which are members 46 the upper ends of which are tilted slightly rearwardly and supported by angular braces 47. The members referred to are relatively reinforced by the reinforcing bars 48 and 75

49 and it will be understood that it is preferred that all of the elements of the combination in the frame be welded for strength and durability.

5 As in the preceding instance, a support 50 is situated approximately midway between the top and bottom of the frame and carries bearings or journal boxes 51. In fact, two sets of such boxes are employed, one set being adapted to receive the ends of a shaft upon which is mounted a 10 winch 52, driven by a chain 53 from a sprocket 54 mounted upon a transverse shaft 55 rearwardly of the frame and this reference will again be made presently. It will be understood that the winch is included in the combination to serve 15 the useful purpose of pulling pump rods, lifting heavy objects around the well, and for other purposes to which it may be applied, and while it is not shown, a suitable clutch is provided on the shaft supporting this winch and is actuated by 20 a hand lever 56.

A motor 57 provides the necessary power for driving the shaft 55 previously referred to through the belt or chain 58 surrounding the armature shaft of the motor and peripherally grooved 25 wheels 59, mounted upon the ends of shaft 60. Belts 61 surround these wheels 59 and counterbalanced wheels 62, mounted upon the ends of shaft 55.

It is apparent from the foregoing that when 30 the motor 57 is set in operation, shaft 60 is rotated and through wheels 59, belts 61 and wheels 62, a pitman like motion is imparted to the member 63. This member is bifurcated or forked, the ends being pivotally joined at 64 to the wheels 35 62 adjacent their peripheries. The upper end of the member 63 is pivotally joined at 65 to one end of the walking beam 66. It is apparent therefore that the operation previously outlined will 40 impart a rocking movement to the walking beam 66.

Near the top of the frame is a shelf or support 67, reinforced by vertical members or brackets 68. Mounted upon this support are bearings 69 in which are journaled stub shafts 70 carried by the links 71. The opposite ends of these 45 links 71 are pivotally joined to a slideable bearing support 72 at 73.

Particular notice will be taken in Figure 9 that the walking beam 66 is displaceably suspended 50 at a point midway between its ends from a shaft 74, whose ends are journaled in bearings 75. The suspending means is comprised of links 76, depending from the shaft 74 and terminating immediately below the bottom surface of the walking beam 66, at which point they are pivotally connected to ear 77, the latter being suitably secured to the beam 66. It will be seen therefore that the beam 66 is capable of slight endwise movement, the links 76 at their lower ends describing 55 an arc when such movement is imparted to the beam. This endwise movement is effective when rocking movement is imparted to the beam by the member 63, as previously described, and the purpose of such movement is to constrain the 60 well pump rods or polished rod to move in a strictly vertical path and thereby reduce lateral stresses thereon, to minimize crystallization of the rods, caused by frictional wear resulting in possible breakage. This displacement of the 65 walking beam is obvious since under ordinary conditions, that is to say when the beam is rocked on a face pivot, it is operative and will describe an arc but by pivotally suspending the fulcrum of the beam the arc is greatly diminished 70 and for all practical purposes the motion 75

imparted to the rods is or might be referred to as perpendicular or in a strictly vertical path. A suitable connection 78 is provided on the operative end of the walking beam for receiving a temper screw connection, which in turn suspends the pump rod assembly. 5

As a means to conserve against sagging or buckling the beam 66 is reinforced at 79 and 80, by plates, suitably secured as by welds on bolts between the flanges of the I beam of which the 10 walking beam is constructed. Moreover, strips or plates 81 are longitudinally disposed at the fulcrum point of the beam both above and below.

Referring again to the adjustable block or member 72 it will be observed that the lower 15 flange of the beam 66 is slotted at A, in Figure 9, to receive the bolts B which hold the block 72 in position. By loosening these bolts, the block may be moved longitudinally of the beam 66 by adjusting the screw or threaded rod 82 passing 20 through the depending and threaded ear 83. Thus the degree of pivotal displacement of the beam is adjusted through the links 71, whose opposite ends are pivotally secured as explained.

Particular notice will be taken that the 25 frame as shown in Figure 1 is identical in construction to that shown in Figure 9 which makes for convenience when it is desired to substitute the cable operated rods for the more rigid walking beam and vice versa. In either case, strain 30 upon the polished rod is reduced to the minimum as apparent.

As a modified example of the counter-balance arm shown in Figures 3 and 4, as previously described, a similar structure is illustrated in Figures 8 and 8a. In this figure, the numeral 84 designates fragmentarily the arms, on the outer surface of each of which, and extending longitudinally is a reinforcing rib 85. The arms are each provided with spaced apertures 86 for receiving the ends of the stub shafts 87, which jointly carry the grooved sheave 88. Lock nuts 89 effectively prevent displacement of the shafts 87. 40

In either of the forms of the invention described, it is highly desirable to provide a simple and efficient counter-balancing means, in addition to the usual form of such means and one which may be adjusted by a single workman. This counter-balance is in the present case embodied in the structure shown in Figures 11 to 14 inclusive and is not only a counter-balance but also a power wheel which may find use in other cases where counter-balanced power is required, for instance in the drilling of wells. 55

The wheel shown is comprised primarily of the rim 90 which may be smooth, annularly grooved or toothed as exemplified in Figures 12, 13 and 14 respectively. The body of the wheel includes the web 91 and what may be conveniently termed 60 a widened spoke 92, connected together by spokes 93, suitably reinforced by webs 94. Diametrical slots 95 are provided both in the web 91 and widened spoke 92 but are not connected. These slots receive bolts 96 for sliding displacement and 65 which secure counter-balance weights 97 in the desired position relative to the rotating axis or hub 78 of the wheel. The flange of the hub, as apparent, is split and may be tightened on a shaft by a suitable set screw or bolt, as illustrated. 70

The enlarged view, Figure 13, shows that the counter-balance weights 97 are grooved to receive the ribs 99. These ribs serve the dual purpose of reinforcing the wheel and also in maintaining the desired rigidity of the counter-balance 75

weights when the latter are placed in accordance with the load and further aid in grinding the weights during adjustment.

Heretofore, it has been the custom to provide 5 a crank and pitman for the transfer of power, the work now performed by the gears 90 and 90a in Figure 14. These gears which are counterbalanced, not only serve more effectively than the crank but likewise dispense with the necessity 10 of providing reduction gears which is an expensive addition and wholly unnecessary when the present invention is employed.

It is apparent therefore that regardless of the size of the wheel and its appurtenances, it will 15 not require more than the services of one man to effect adjustment of the weights. This wheel is adapted for use on both the forms of the invention shown and described.

Manifestly, the construction shown is capable 20 of considerable modification and it will be understood that such modification as may fall within the meaning and scope of the appended claims is likewise considered within the spirit and intent of the invention.

25 What is claimed is:

1. A well pumping unit including a frame and a walking beam, means for swingingly suspending said beam from the top of said frame intermediate its ends, counter-balanced means for 30 transmitting to said beam a rocking motion, means adjacent the fulcrum point of said beam operatively for holding the swinging movement of said beam within predetermined limits to constrain the outer end thereof to move rectilinearly, 35 means for adjusting the extent of said swinging movement, said means being also effective for longitudinally displacing said beam from its operative position.

2. In a well pump as defined in claim 1, in 40 which the means for limiting the swing of said beam is capable of being adjusted to increase and decrease the range through which said beam swings.

3. A pumping unit for wells including vertical 45 uprights and a walking beam, means pivotally suspending said beam intermediate its ends from a point above its major axis to said uprights, said means constituting the sole support of said beam,

means pivotally connected indirectly to said uprights on either side of said beam and having common pivotal connection with said beam between one end and its fulcrum to constrain the beam to move longitudinally during its travel above and below the horizontal plane and means to effect longitudinal displacement of said beam from its operative position.

4. In a pumping unit, a walking beam support, a walking beam, means comprising the sole support for said beam and pivotally suspending the same for limited longitudinal displacement from said support at a point above its major axis, means connected to said beam between an end thereof and its fulcrum and disposed on either side thereof to hold said beam against lateral displacement and to constrain the ends thereof to follow a substantially vertical line when said beam is rocked on its fulcrum.

5. In an apparatus for operating wells, a walking beam and support, a pair of parallel links pivoted to the top of said support and to the underside of said beam for suspending said walking beam from said support at a point approximately midway between its ends whereby its fulcrum will be capable of swinging relative to its point of suspension, means connected to said beam and to said support for positively resisting the axial thrust of said beam to constrain its ends to move on a substantially vertical path.

6. In an apparatus for pumping wells, a walking beam, and a support therefor, a member pivoted to the top of said support and to a point below the longitudinal axis of said beam for suspending the full weight of said walking beam relative to said support at its fulcrum whereby the weight of the beam will have a tendency to displace its fulcrum relative to its point of suspension at each extreme position thereof, means on either side of the beam having connection between the latter and its support for holding within predetermined limits the displacement of said beam to cause its ends to travel in substantially vertical planes and to hold said beam against lateral displacement.

GEORGE T. HUMPHREY.
